UNITED STATES PATENT OFFICE

147,584

DESIGN FOR A BOTTLE CARRIER

Forrest K. Gibson, Houston, Tex.

Application December 5, 1945, Serial No. 124,397

Term of patent 14 years

(Cl. D58—4)

To all whom it may concern:

Be it known that I, Forrest K. Gibson, a citizen of the United States, residing at Houston, in the county of Harris in the State of Texas, have invented a new, original, and ornamental Design for a Bottle Carrier, of which the following is a specification, reference being had to the accompanying drawings, forming a part thereof.

Figure 1 is a plan view of a bottle carrier, showing my new design.

Figure 2 is a side elevational view,

Figure 3 is an end view,

Figure 4 is a side elevation, partly in section, and

Figure 5 is an end view, partly in section.

I claim:

The ornamental design for a bottle carrier, as shown.

FORREST K. GIBSON.
